DESIGN FOR A DOORLATCH

Sigurd Brantingson, Palisades Park, N. J., assignor to Francis Keil & Son, Inc., a corporation of New York

Application June 29, 1934, Serial No. 52,389

Term of patent 14 years

To all whom it may concern:

Be it known that I, SIGURD BRANTINGSON, a subject of Sweden, and a resident of Palisades Park, in the county of Bergen and State of New Jersey, have invented a new, original, and ornamental Design for a Door Latch, of which the following is a specification, reference being had to the accompanying drawing, forming a part hereof.

In the drawing,

Figure 1 is a side elevation, and Figure 2 is a plan view, of a latch showing my new design.

I claim:

The ornamental design for a door latch substantially as shown.

In witness whereof, I have signed my name to this specification, this 27th day of June, 1934.

SIGURD BRANTINGSON.
